UNITED STATES PATENT OFFICE.

THOMAS G. PLANT, OF BOSTON, MASSACHUSETTS, ASSIGNOR TO UNITED SHOE MACHINERY COMPANY, OF PATERSON, NEW JERSEY, A CORPORATION OF NEW JERSEY.

EDGE-PROTECTOR FOR SHOE-SOLES.

1,124,328.

Specification of Letters Patent. Patented Jan. 12, 1915.

Application filed June 11, 1909. Serial No. 501,448.

To all whom it may concern:

Be it known that I, THOMAS G. PLANT, a citizen of the United States, residing at Boston, in the county of Suffolk and State 5 of Massachusetts, have invented an Improvement in Edge-Protectors for Shoe-Soles, of which the following description, in connection with the accompanying drawings, is a specification, like letters on the 10 drawings representing like parts.

The invention herein to be described relates to means for protecting the edges of shoe soles during treatment of the upper, and has for its aims and purposes the protection of a guard that may be conveniently employed to shield the sole edge while the upper of the shoe is being treated, all as will hereinafter more fully appear in connection with the accompanying drawings, 15 showing one form or embodiment of the various expedients that may be adapted in carrying the invention into practical effect, it being understood that the invention is not circumscribed by the details of such embodiment but is definitely set forth by the 20 claims.

In the drawings: Figure 1 is a plan view of a device embodying the present invention, said device being illustrated as positioned on a shoe; Fig. 2 is a section on the line 2—2, Fig. 1; Fig. 3 is a detached detail view of a portion of the protector looking from beneath; Fig. 4 is a section on line 4—4, Fig. 3, with the protector shown in the 25 relative positions of its parts as they appear when the protector is applied to a shoe; Fig. 5 is a detached detail showing the end of one of the plates or members; Fig. 6 is a like view of one end of the other plates or 30 members; Fig. 7 is a cross section on line 7—7, Fig. 2; and Fig. 8 is a section on line 8—8, Figs. 2 and 7.

The edge protector is adapted to be applied to a boot or shoe above the projecting 45 edge *a* of the sole, the boot or shoe being typified in Figs. 1 and 2 by *A*, and when in position it is designed to protect the edge or surface of the sole during the application of any finishing material or other substance to the shoe upper, or during any 50 treatment of the shoe upper under condition

that might subject the surface or edge of the sole to injury or discoloration.

In the present form of the invention the protector comprises a series of plates flexibly united in a manner that they may be readily and conveniently applied to any shoe, one edge of the protector extending over the top of the sole into proximity with the inseam, as typified in Fig. 2. 55

The plates of the protector may be formed conveniently in any suitable manner and flexibly joined together by suitable means, the invention in this respect being generic. In the form of the invention illustrated, each of a series of plates 1 has stamped therefrom the side fingers 2, 2, adapted to engage a suitable hole 3 in each of a series of plates 4, said holes 3 extending longitudinally of the plates 4 to an extent sufficient to permit the fingers 2, 2, to be engaged therewith when the said fingers are in longitudinal alinement with said hole 3 but preventing disengagement therefrom when the fingers extend transversely thereof, as indicated in Figs. 1 and 3. Each of the plates 1 is also provided with downturned portions 5 which likewise extend through the holes 3 of the adjacent plates 4, as will be clearly apparent from Figs. 1, 3 60 and 4, and the downturned portions 5 on the adjacent ends of adjoining plates 1 are connected by flexible means, such as the springs 6, the construction being such that the springs 6 normally act to draw the plates 1 toward each other, or in other words normally contract the protector, so that it may readily adapt itself to different sizes and styles of shoes, and when in position it will have the inner edges of the series of plates thus assembled extend well 65 into the space between the upper and sole in proximity to the seam, as indicated in Fig. 2. 70

The protector, or series of plates flexibly 75 convenient application and removal of the united as described or otherwise, is connected to a protector carrier which is expansible and contractible to facilitate the ready and protector to and from a boot or shoe. In 100 the illustrated form of the invention the protector carrier comprises the telescopic

slides 7 and 8, Figs. 2 and 7, each having an upright supporting arm 9 and 10 respectively. At their upper portions the arms 9 and 10 are turned or bent, as at 11, and have 5 pivotally connected thereto at 12, 12 the series of plates as indicated in Figs. 1 and 2. Obviously the protector, or series of plates, could be connected to the carrier at any convenient point in the length of the 10 protector, but in the present form of the invention the end plate at each side of the protector is provided with a projection 13 which affords a convenient means for the pivotal connection of the protector with the 15 protector carrier.

The protector carrier member or slide 8 is formed as a casing, see cross section thereof in Fig. 7, and has secured thereto by screws 15 a rack bar 14 provided with the 20 teeth 16. The coacting slide member 7 is formed as indicated in cross section, Fig. 7, and extends into the casing of slide member 8. At its inner edge portion the slide 7 is provided with a rack bar 17 secured thereto by pins or other means 19 and is provided with teeth 18 which coact with the teeth 16 on the rack bar 14. The slide 7 has the 25 downturned flange 20, Fig. 7, which with the slide 8 serves to complete the casing 30 character of the telescopic slides so that they may be grasped by the hand, and disposed between the flange 20 of the slide 7 and the untoothed edge of the rack bar 14 secured to the slide 8 is a spring 21, Figs. 35 7 and 8, the construction being such that the spring 21 normally holds the rack teeth of the rack bar in engagement, permitting them to slide over each other in one direction to contract the carrier, and locking them 40 against movement in the opposite direction, as will be apparent.

From the construction described it will be obvious that the carrier may be grasped by the hand and, upon relative movement of 45 the members 7 and 8 transversely under pressure of the hand, the spring 21 will be compressed and the teeth 16 and 18 of the rack bars will be disengaged, thereby permitting the telescoping members 7 and 8 to 50 be separated, so as to open the protector that it may be properly applied to a shoe, as hereinbefore indicated. When the protector has thus been applied to the shoe and the 55 inner edge of the series of plates rests between the upper and the sole, as in Fig. 2, the telescoping members 7 and 8 may be slid longitudinally to contract the carrier to bring the parts of the protector snugly into position, the spring 21 at such times yielding and then serving to lock or hold the 60 teeth 16 and 18 in engagement to prevent expansion of the carrier and hold the protector firmly in position on the shoe.

Obviously the form and character of the carrier may be varied within wide limits, 65 and various means may be employed to form the ready expansion and contraction of the edge protector so that it may be readily applied to and removed from its position on the shoe.

The edge protector thus far described has been especially adapted for the forepart of a shoe, as indicated in Fig. 1, and in such construction the toe portion of the protector is preferably formed by two plates 22 and 70 23 hinged together by a pin 24, as indicated in Fig. 1, the other ends of said plates 22 and 23 being otherwise formed for coaction with the other plates of the series, as hereinbefore pointed out. It is desirable that the 80 shank portion of the shoe shall be protected when the shoe upper is being treated at this point, and for this purpose the edge protector is provided with shank plates 25, one being pivoted to each of the end plates, 85 as at 26, and normally pressed inward or toward the shank of the shoe by means of suitable springs 27. These springs may be supported in any suitable manner to perform the described function, and are herein 90 designated as wound about the pivotal studs 12 connecting the protector carrier with the edge protector, the end of the spring adjacent the pivotal points 12 being secured to the end plates of the edge protector, and 95 the opposite ends of the springs being secured, as at 28, to the shank plates. Obviously the character of the plates for protecting the shank portion of the shoe may be variously formed, and in some cases may 100 not be necessary.

It is sometimes desirable that the heel portion of the sole edge be protected during treatment of the upper portion of the shoe at the heel, and to this end a heel edge protector may be provided and formed of a 105 series of plates substantially the same as those described for the forepart protector, and indicated in part by dotted lines in Fig. 1. The heel edge protector may likewise be 110 provided with shank members 29 which may be pivotally supported at 31 on a suitable heel edge protector carrier 30 substantially the same as the protector carrier hereinbefore described, or of any suitable and 115 desired character.

While the edge protector hereinbefore set forth has embodied various details of construction and is shown as applied to the forepart or to the heel part of the shoe, it 120 is obvious that it may be variously formed, that its details or construction may be varied within wide limits without departing from the spirit of the present invention, and that it may be made of greater or less 125 extent according to the desired use of the

edge protector, the invention being generic in these respects.

What is claimed is:

1. A protector for the edges of boot and shoe soles, comprising a series of plates flexibly connected together to conform to the varying contours of shoe soles at the sides thereof, said plates having overlapping parts overlying the top of the sole to form an uninterrupted covering therefor and extending into the crease between the sole and upper.
2. A protector for the edges of boot and shoe soles, comprising a series of plates arranged to extend along the sides of the fore-part and about the toe of the shoe, means connecting the plates of the series permitting said plates to conform to both sides and toe portions of the shoe, and a shank protecting member to protect the edge of the sole along the shank.
3. A protector for the edges of boot and shoe soles comprising a series of plates yieldingly connected in a longitudinal direction and arranged to overlie the projecting edge of the sole and conform to the outline of the shoe, and a carrier for said protector.
4. A protector for the edges of boot and shoe soles comprising a series of articulated plates yieldable longitudinally and arranged to overlie the protecting edge of the sole and conform to the outline of the shoe, and an expansible and contractible carrier for said protector.
5. A protector for the edges of boot and shoe soles comprising a series of plates having side portions to engage the sides of a shoe, said side portions being flexibly connected together to conform to the varying contours of shoes at the sides thereof, said plates having parts overlying the top of the sole arranged to form an uninterrupted covering therefor and extending into the crease between the sole and upper.
6. A protector for the edges of boot and shoe soles comprising a series of plates arranged to overlie the projecting edge of the sole, means for yieldingly connecting said plates longitudinally, and means for holding the plates in said position to protect the sole edge during treatment of the upper portion of the shoe.
7. A protector for the edges of boot and shoe soles, comprising a series of plates flexibly connected to permit said plates to conform to the contour of a shoe above the sole edge and move relatively in a longitudinal direction, and means normally acting to hold said series of connected plates in contracted relation.
8. A protector for the edges of boot and shoe soles, comprising a series of plates flex-

ibly connected together where they extend along the sides and about the toe to permit 65 said plates to conform to the contour of a shoe above the sole edge, yielding means normally acting to hold said series of connected plates in contracted relation, and a carrier for said protector.

9. A protector for the edges of boot and shoe soles, comprising a series of plates extending along each side of the shoe and flexibly connected to permit said plates to conform to the contour of a shoe above the 75 sole edge, and a spring connection between some of said plates acting to normally contract the length of the protector.

10. A protector for the edges of a boot or shoe sole comprising a series of articulated 80 plates extending along each side of the shoe and arranged to overlie the sole edge, a carrier for said protector having telescopic members, and means for holding the members in contracted relation with the protector in position on the boot or shoe.

11. A protector for the edges of a boot or shoe sole comprising series of articulated plates extending along each side of the shoe and arranged to overlie the sole edge, a carrier for said protector having relatively 90 movable slide members, and means for locking the slide members from relative movement.

12. A protector for the sole edge of a boot 95 or shoe arranged to overlie the sole edge and extend into the crease between the upper and sole, and having a shank protecting member, said shank protecting member extending toward the heel portion of the shoe 100 from the ball line.

13. A protector for the sole edge of a boot or shoe arranged to overlie the sole edge and extend into the crease between the upper and sole, and having a spring-controlled 105 shank protecting member.

14. A protector for the edges of boot and shoe soles, comprising a series of members having pivotal relation and longitudinal movement with respect to each other to enable said members to mutually adapt themselves to varying contours of the shoe along the sides and about the toe, and means for locking the protector in protecting position.

15. A protector for the edges of boot and shoe soles, comprising a series of members having pivotal relation and longitudinal movement with respect to each other to enable said members to mutually adapt themselves to varying contours of the shoe along the sides and about the toe, means for locking the protector in protecting position, and a shank protecting member extending from the said series of members.

16. A protector for the edges of boot and 125 shoe soles, comprising a series of plates piv-

otally connected together along the sides and toe protecting portions of said protector to enable the plates to accommodate themselves to varying forms or contours of 5 shoes along the sides and about the toe, the pivotal connection between said plates being constructed and arranged to permit said plates to move relatively in a longitudinal direction.

10 17, A protector for the edges of boot and shoe soles, comprising a series of plates piv- otally connected together along the sides and

toe protecting portions of said protector to enable the plates to accommodate themselves to varying forms or contours of shoes along 15 the sides and about the toe, and a shank plate conformable to the shank of the shoe.

In testimony whereof, I have signed my name to this specification, in the presence of two subscribing witnesses.

THOMAS G. PLANT.
